UNITED STATES PATENT OFFICE.

HERBERT BIRD, OF READING, ENGLAND.

APPARATUS FOR CHARGING GAS-RETORTS.

1,256,650.

Specification of Letters Patent. Patented Feb. 19, 1918.

Application filed August 26, 1916. Serial No. 117,033.

To all whom it may concern:

Be it known that I, HERBERT BIRD, engineer, of the Kennet Iron Works, Reading, in the county of Berkshire, England, subject of the King of Great Britain and Ireland, have invented certain new and useful Improvements in and Relating to Apparatus for Charging Gas-Retorts, of which the following is a specification.

- 10 This invention relates to apparatus for charging gas retorts of the type in which a scoop is suspended from a traveling crane, and adapted to be moved longitudinally and transversely of the retort house and to be raised and lowered and swung horizontally on a pivot so as to be readily filled with coal and inserted in the retort, the coal being held in the retort while the shell of the scoop is withdrawn.
- 15 In apparatus for charging retorts of the type in which the scoop is mounted on a carriage adapted to run on the floor of the retort house it has been proposed to put the scoop into the retort by means of a rack disposed beneath the scoop.
- 20 In apparatus for charging retorts of the type in which the scoop is mounted on a carriage adapted to run on the floor of the retort house it has been proposed to put the scoop into the retort by means of a rack disposed beneath the scoop.

The object of this invention is to provide an improved apparatus of the suspended type in which a longitudinal rack is disposed on the underside of the scoop.

25 Referring to the accompanying drawings:—

Figures 1 and 1^a show an end view of one form of apparatus made in accordance with this invention;

30 Fig. 1^b is an enlarged view of the rack and channel;

35 Figs. 2 and 2^a show a side elevation of the apparatus shown in Figs. 1 and 1^a.

Fig. 3 is a plan showing holding dogs, drum, and automatic changing gear;

40 Fig. 4 is a detail showing the rack;

Fig. 5 is a cross-section showing reversing gear and winding drum;

45 Fig. 6 is a part plan showing clutch operating device;

Fig. 7 is a part plan showing the pivotal mounting of the vertical frame;

Fig. 8 is a perspective view of the sliding frame adapted to hold the coal in the retort when the scoop is being withdrawn;

50 Fig. 9 is a part elevation and

Fig. 10 is a part plan, showing the manner in which the sliding frame is held.

55 Fig. 11 is a horizontal section of Fig. 2 showing hand operating gear.

In a machine shown in the drawings, the

horizontal frame *a* of the machine is supported on a cradle *b*. The horizontal frame may consist of two channel beams *c c* suitably spaced apart. The cradle *b* and horizontal frame *a* are disposed between four members *d d d d* of a vertical frame. The four members *d d* of the vertical frame are fixed at the upper end of a casting *d'* shown on plan in Fig. 7, which is suspended from a similar casting *d²* by a pivot bolt *d³* in such manner that the said casting *d'* and vertical frame attached and the whole machine below the casting *d²* can turn in a horizontal plane to any desired angle. To the casting *d²* are attached the sides of a traveler carrying traveling wheels and axles. The vertical frame acts as a guide to the cradle *b* or horizontal frame *a* and is pivotally connected to the traveler *e* so as to permit of its being turned in a horizontal plane and carries at its upper end two pulleys *f f* operated by a hand wheel *g* through a worm *h* and worm wheel *j*, bevel gearing *k* and shafting *m*. The cradle *b* and horizontal frame *a* are suspended by ropes *n n* which pass over these pulleys *f f* and are counter-balanced by the weight *o*. Upon the vertical frame *d d* is mounted vertical shafting *p* for operating the scoop by means of the hand wheel *g*. Between the shafts *m* and *p* and in line therewith is an intermediate shaft *p²* provided with a short feather and carrying a clutch *p'* rotating therewith and adapted to slide thereon. Loosely mounted on the shaft *p²* are two bevel wheels *k k*, adapted to be connected to and disconnected from the shaft by the clutch device *p'*. Gearing with the bevel pinions *k k* is a bevel pinion *k'* mounted on a short shaft *g³*. The handwheel *g* is provided with a boss *g⁴* which is keyed at *g⁴* to the shaft *g³*. The shaft *g³* is mounted on a bearing *g'* which extends from the bracket *g²*.

50 The shaft *p²* is adapted to be connected either to the shaft *m* or to the shaft *p* by the clutches *p³ p⁴* adapted to be operated in any well known manner.

When hand wheel *g* is connected to drive *m*, the lifting and lowering of the scoop and horizontal frame is accomplished through worm *h* and worm *j* and pulleys *f f*, Fig. 1, keyed to the same shaft as worm *h*, which shaft runs in roller bearings in casting *d²*, Fig. 4. When hand wheel *g* is connected to drive *p*, the gear wheels *p⁵* drive vertical

shaft t , see Figs. 2^a and 3, and, through miter wheels t' the main shaft t^2 . On this main shaft is keyed a chain sprocket wheel t^3 , adapted to drive through the pitch chain 5 t^4 , the sprocket wheel r' , shaft r , pinion w and spur wheel v , which actuates the rack fixed to the underside of the scoop. The miter wheel on vertical shaft t has a keyway sliding easily upon a long feather fixed 10 to the shaft, to accommodate the varying height of frame a . The horizontal frame a carries shafting $q r s t$, gear wheels $v w x$, clutch mechanism y , reversing gear and winding drum 2. On cradle b of the horizontal frame a are rollers 3 3 3 3 which work in the vertical guides and other rollers 4 4 5 5 on which the scoop 6 travels. The scoop is provided on its underside with a longitudinal rack 7, formed of bars 7¹, which 15 is adapted to be operated by the toothed wheel v mounted on the shaft q disposed on the horizontal frame. The upper edges of the scoop 6 are flanged as at 8 or otherwise formed to carry a sliding frame 9 9 on 20 which are pivoted flaps 10, 11, 12, one being at the forward end and one or more intermediate of its length. The sliding frame 9 consists of two light channel irons 9^a into 25 the grooves of which the flanged edges of the scoop project, held together by three or more cross angle irons 9^b on which are hinged the flaps 10, 11, 12, Fig. 8. These flaps are flanged or bent back at the sides as at 10^a, 11^a, 12^a, Fig. 8, so that they can only 30 turn on their hinges in one direction, that is, while the frame 9 is being withdrawn from the retort, but will hold the coal in the retort when the scoop is withdrawn. When 35 the scoop is being withdrawn, the frame 9 is held stationary by the pawl 14^a and notches 14^b in channel 14. The channel 14 is provided at its rear end with a dead eye 14^c. The channel irons c c are provided 40 with brackets c' , c' . A pin c^2 passes 45 through the dead eye 14^c and supports the channel 14. The top edges 10^a, 11^a and 12^a of the flanged sides of the flaps bear against 50 the cross angle irons 9^c supporting them so forming stops to retain the flaps in a vertical position against the pressure of the coal which, but for the resistance of the flaps, would be drawn out with the scoop. The rear end of the scoop is closed by a plate 55 13. The plates 11, 12 and 13 are notched, 11^b, 12^b and 13^b, see Fig. 8, at the base to allow them to pass along the channel 14 which extends into the scoop. The channel 14 is attached at its rear end to the channel irons c by brackets c' and pin c^2 which 60 passes through a dead eye mounted on the rear end of channel 14. The front end of the channel 14 is provided with notches 14^b. The back end of the sliding frame 9 is provided with a pawl which is adapted to engage in said notches disposed on the longi-

tudinal channel 14. The rear end of the sliding frame 9 is connected to the winding drum 2 by a steel rope or chain 15. The rope or chain 15 is utilized for the purpose of lifting the pawl out of engagement with the notches in the channel 14 when a strain is put on the rope for the purpose of withdrawing the sliding frame 9, and for this purpose the rope 15 is passed through an eye in the pawl, the arrangement being such that when the rope is slack, the pawl falls into the notches but when tight the pawl is lifted out of the notches. Means for locking the apparatus rigidly to the front of the retort when the apparatus is in use 70 comprises dogs 16 suitably pivoted and operated by a bent lever 17 through rods 18. 75

On the side and at the rear end of the channel c is pivoted a catch 20 adapted to engage a projection 21 on the rod 22. The rod 22 when retained by the projection 21 is pressed longitudinally by the spring 23. On the catch 20 is an inclined plane 20^a. 80

The clutch y is normally in a position for traversing the scoop in and out of the retort. This clutch is adapted to be operated by rod 22, see Figs. 3 and 6. The rod 22 is held in position by catch 20 pivoted on one of the channel beams c , one arm of the catch 20 engaging a projection 21 on the rod 22. 95 Spring 23 tends to push the rod 22 endwise to shift the clutch y from a position to operate the scoop to a position to operate the sliding frame 9. The lever 20 has a cam or inclined plane 20^a which is adapted to be struck by the scoop when retracted and to lift the other end of the lever out of engagement with the projection 21. 100

In operation the scoop 6 is filled with coal from a hopper 19 or otherwise. It is then 105 traversed to any desired position of the retort house by means of the traveling crane. It is then raised or lowered to the level of the retort mouth by means of the central hand wheel g and swung on its pivot to a position 110 to enter the mouth of the retort. Many of the retort houses are cramped and the ability to rotate the scoop facilities the handling of the machine. The end of the scoop 6 is then run into the mouth of the retort as far 115 as the horizontal frame a will permit; the scoop 6 and sliding frame 9 are then traversed forward by rack 7 and gear v operated by the central hand wheel g . The scoop 6 is then withdrawn by operating the handle g in 120 the reverse direction or by reversing the gear z , leaving the coal and the sliding frame 9 in the retort. After the scoop has been withdrawn the sliding frame 9 is retracted. When the scoop strikes the inclined plane 20^a, the catch 20 is raised above the projection 21 on the rod 22. The spring 23 forces the rod 22 endwise and automatically 125 throws the clutch y out of the gear operating the scoop into the gear operating the sliding 130

frame 9, so that when the handle 7 is further rotated, tension is placed on the wire rope 15 which automatically lifts the pawl 14^a from the notches 14^b in channel 14 and allows the sliding frame 9 to be withdrawn, to a position ready to be reloaded, leaving the coal in the retort.

The flaps rise as the sliding frame is withdrawn and pass over the surface of the coal to level it.

In some cases a rack 24 may be fixed at the end of the sliding frame 9 so that the sliding frame may be pushed forward while the scoop remains stationary.

15 What I claim and desire to secure by Letters Patent is—

1. Apparatus for charging gas retorts comprising a cradle, a scoop mounted on said cradle, means for moving said cradle longitudinally and transversely of the retort house, means for raising, lowering and rotating said cradle, horizontally, means for projecting and retracting said scoop relatively to said cradle, said means comprising a frame 20 attached to the cradle, a toothed wheel mounted on a shaft on said frame, means for rotating said shaft, rollers on said frame on which the said scoop is supported, a rack disposed below said scoop and attached thereto, said rack being adapted to engage said toothed wheel.

2. Apparatus for charging gas retorts comprising a cradle, a scoop mounted on said cradle, means for moving said cradle longitudinally and transversely of the retort house, means for raising, lowering and rotating said cradle, horizontally, means for projecting and retracting said scoop relatively to said cradle, said means comprising 35 a frame attached to the cradle, a toothed wheel mounted on a shaft on said frame, means for rotating said shaft, rollers on said frame on wh'ch the said scoop is supported, a rack disposed below said scoop and attached thereto, said rack being adapted to engage said toothed wheel, a sliding frame 40 mounted on said scoop, pivoted flaps on said sliding frame, stops on said flaps so disposed that said flaps will not turn on their pivots when the scoop is withdrawn, means for projecting said sliding frame with said scoop into the retort, means for leaving said sliding frame in the retort until after the said scoop has been withdrawn, means for retracting said frame, said means comprising a winding drum mounted on a shaft on said frame and a wire leading from the said drum to the rear end of the said sliding frame, and automatic means for throwing the winding drum into action to retract the sliding frame as soon as the said scoop has 45 been withdrawn.

flaps on said sliding frame, stops on said flaps so disposed that said flaps will not turn on their pivots when the scoop is withdrawn, means for projecting said sliding frame with said scoop into the retort, means for leaving said sliding frame in the retort until after the said scoop has been withdrawn, and means for retracting said frame. 50 55

3. Apparatus for charging gas retorts comprising a cradle, a scoop mounted on said cradle, means for moving said cradle longitudinally and transversely of the retort house, means for raising, lowering and 60 rotating said cradle horizontally, means for projecting and retracting said scoop relatively to said cradle, said means comprising a frame attached to the cradle, a toothed wheel mounted on a shaft on said frame, 65 means for rotating said shaft, rollers on said frame on which the said scoop is supported, a rack disposed below said scoop and attached thereto, said rack being adapted to engage said toothed wheel, a sliding frame 70 mounted on said scoop, pivoted flaps on said sliding frame, stops on said flaps so disposed that said flaps will not turn on their pivots when the scoop is withdrawn, means for projecting said sliding frame with said 75 scoop into the retort, means for leaving said sliding frame in the retort until after the said scoop has been withdrawn, means for retracting said frame, said means comprising a winding drum mounted on a shaft on said frame and a wire leading from the said drum to the rear end of the said sliding frame, and automatic means for throwing the winding drum into action to retract the sliding frame as soon as the said scoop has 80 85 been withdrawn.

In witness whereof, I have hereunto signed my name in the presence of two subscribing witnesses.

HERBERT BIRD.
